UNITED STATES PATENT OFFICE.

FRANK EARL MARCY, OF SAN DIEGO, CALIFORNIA.

GRATE FOR BALL MILLS AND METHOD OF MAKING SAME.

Application filed November 22, 1926. Serial No. 150,072.

This invention relates to an improvement in grates which are used in ball mills for crushing ores or the like. In one type of such mill there is placed near the discharge end 5 a separating screen or grate to allow the properly ground material to pass out. This general type of mill is shown in my Patent 1,153,239, September 14, 1915, and the present invention is an improvement on the form of grate described therein.

Due to the severe service to which these grates are put, difficulty has been experienced in securing the individual grate bars in place such that they will not become dislodged when they are partly worn. Sometimes these bars slip sidewise and thus vary the opening between them. Also, the bars may slip endwise and fall completely out of their frame.

It is an object of this invention to provide a grate in which the grate bars are rigidly and firmly secured to the supporting frame.

Another object of the invention is to provide a grate wherein the bars are so secured that they cannot work loose when they are worn down in use.

These and other objects will be apparent from the following description taken in connection with the accompanying drawings wherein

Fig. 1 is a front elevation of a completed grate section, with one corner broken away;

Fig. 2 is a fragmentary sectional view, 35 showing the means of connecting the grate sections to a spider frame;

Fig. 3 is an enlarged fragmentary end view of an end of the grate, one grate bar being partly broken away, and

Fig. 4 is a similar fragmentary view of a modified form.

The assembled grate bars, as shown in Fig. 1, comprise one of a series of similar members arranged about a common axis, as is clearly shown in my Patent 1,153,239, September 14, 1915. Numeral 1 indicates the individual grate bars, which are made progressively shorter, as seen in Fig. 1, and are preferably made of special high carbon, chrome steel. Each end of these grate bars is formed at an angle to the longitudinal axis of the bar, so that one edge is longer than the other. These sloping ends make an angle of approximately 66° with the longitudinal faces, or in other words angle

A (see Fig. 3) is about 66°. These sloping end faces of the bars are further cut back, as seen in Figs. 2 and 3, to provide a projecting lug or lip 2 at the rear of the bars.

The individual grate bars are aligned in parallel relation and properly spaced from one another as seen in Fig. 1, and a cross-rod of metal 3, preferably steel, is placed upon these projecting lugs or lips, said rod having upset ends 4. In Fig. 1, two longitudinally aligned cross-rods are shown on each side of the completed grate section, but it is obvious that this is not essential, as in some cases only one rod may be needed, or possibly three or more rods. With the grate thus assembled, a steel jacket or binder 5 is then cast around the ends of each grate bar. This jacket completely encloses the cross-rods and the ends of the grate bars, and extends between the separated bars a distance equal to the cut-back on the ends of the bars. This will be clear from Figs. 3 and 4 wherein the front grate bar is broken away to show the cast metal 5 extending between the bars. In the modified form as shown in Fig. 4, the lips or lugs 2 are made hook-shaped to thereby partially enclose the cross-rods 3. This construction is easier to assemble and stronger than that shown in Fig. 3.

The grate bars are thus united into a rigid section as shown in Fig. 1. A plurality of these sections are clamped to a spider having arms 6 which are engaged by the rear faces of adjacent lateral edges of each two grate sections, as seen in Fig. 2. A clamp bar or member 7 is placed between adjacent grate sections, said member having openings 8 therethrough to receive bolts 9, having heads 10. The bolts 9 pass through the spider 6 and openings 8 are countersunk to take heads 10. At their other ends the bolts are screw-threaded to receive nuts 11 for engagement against face 12 of the spider 6.

The material which has been ground passes horizontally through the grate (or from above, as seen in Fig. 2).

The front surface of the grate section wears away in use, and the cast metal fins may become separated from the adjacent grate bars. The transverse steel rods lock the cast metal in place to prevent relative displacement of the bars and cast metal. The grates may therefore be used until worn so thin as to be structurally weak.

The embodiment shown is for illustrative purposes only, and the invention is limited only in so far as set forth in the following claims.

5. I claim:—

1. The method of uniting a plurality of grate bars, having a projecting lug at each end thereof into a rigid grate section, which comprises arranging the bars in parallelism 10 with the projecting lugs at the respective ends of the bars in alignment, placing a metallic rod along the ends of the bars and resting on said lugs, and casting a steel binder along the ends of the bars and enclosing said rod.

2. A grate section for ball mills comprising, in combination, a plurality of grate bars in parallelism, the ends of the bars being recessed to provide lips on the ends, a 20 steel rod resting on the aligned lips at each end of the bars, and a side strip of metal cast upon and enclosing each of said rods and the bar ends adjacent thereto.

3. The structure as in claim 2 wherein the 25 lips on the ends of the bars are hook shaped.

4. The structure as in claim 2 wherein the ends of the steel rods are upset.

5. A grate section for ball mills of the 30 type wherein a plurality of grate bars are held rigidly in parallel spaced relation, characterized by the fact that the ends of the bars are joined by means of a steel binder

cast upon the ends of the bars and having embedded therein a transverse steel rod.

6. A grate section for ball mills of the 35 type wherein a plurality of grate bars are held in parallel spaced relation, characterized by the fact that the bars are provided with a projecting lug on each end, and a cross rod, having upset ends, is held in rigid 40 engagement with said lugs by an encasing steel jacket cast in situ.

7. A grate section for ball mills of the type wherein a plurality of grate bars are held in rigid parallelism, by binding strips 45 of metal cast upon the ends thereof, characterized by the fact that each grate bar has an overhanging hook on its ends, and a steel rod is engaged by the said hooks, said metallic binding strip enclosing said hooks 50 and the steel rod.

8. A grate section comprising a plurality of grate bars in spaced and substantially parallel relation, a body of metal cast upon 55 said bars and having fins extending between adjacent bars to retain the same in said spaced relation, and a rod embedded in said cast metal, said rod preventing displacement of individual fins of cast metal if the bond between the fin and an adjacent bar is 60 destroyed.

In testimony whereof, I affix my signature.

FRANK EARL MARCY.
